US0D1046167S

(12) **United States Design Patent** (10) **Patent No.:** **US D1,046,167 S**
(45) **Date of Patent:** **** Oct. 8, 2024**

(54) **SKIN TREATMENT DEVICE AND CAP**

(71) Applicant: **LUMENIS BE LTD.**, Yokneam (IL)

(72) Inventor: **Noam Tenenbaum**, Kadima (IL)

(73) Assignee: **LUMENIS BE LTD.**, Yokneam (IL)

(**) Term: **15 Years**

(21) Appl. No.: **29/850,111**

(22) Filed: **Aug. 17, 2022**

(51) **LOC (14) Cl.** **24-01**

(52) **U.S. Cl.**

USPC **D24/200**

CLAIM

The ornamental design for a skin treatment device and cap, as shown and described.

DESCRIPTION

FIG. 1 is a Front View of the new design.

FIG. 2 is a Right View of the new design.

FIG. 3 is a Top View of the new design.

FIG. 4 is a Bottom View of the new design.

FIG. 5 is a Left View of the new design.

FIG. 6 is a Back View of the new design.

FIG. 7 is a Top Right Perspective View of the new design.

FIG. 8 is a Top Left Perspective View of the new design; and,

FIG. 9 is a Bottom Perspective View of the new design.

The broken lines shown in the FIGS. 1-9 illustrate portions of the skin treatment device and cap that form no part of the claimed design.

1 Claim, 9 Drawing Sheets
